J. C. DAWSON

LOOSE LEAF BINDER

Filed Dec. 15, 1924

Inventor:
By James C. Dawson
Gillmor, Mann & Cox
Attest.

UNITED STATES PATENT OFFICE.

JAMES C. DAWSON, OF WEBSTER GROVES, MISSOURI, ASSIGNOR TO ELMA N. DAWSON,
OF WEBSTER GROVES, MISSOURI.

LOOSE-LEAF BINDER.

Application filed December 15, 1924. Serial No. 755,897.

This invention relates to loose leaf binders, and one of the objects of the invention is the provision of new and improved means for attaching the paper-retaining prongs rigidly in position in their supports.

Another object of the invention is the provision of new and improved means for attaching a book binder assembly or mechanism to a book cover in an effective and simple manner.

Other objects of the invention are the provision of a new and improved loose leaf binder assembly or mechanism, together with new and improved means for mounting the same on a book cover, that are simple in construction, cheap to manufacture, easily assembled, efficient in operation, and that are not likely to become broken or get out of order.

Other and further objects and advantages of the invention will appear from the following description taken in connection with the accompanying drawings, in which—

Fig. 1 is a top plan view of the paper holding mechanism;

Fig. 2 is an end view showing the mechanism attached to a book cover;

Fig. 3 is a section on line 3—3 of Fig. 2;

Fig. 4 is a section on line 4—4 of Fig. 1;

Fig. 5 is a perspective of a portion of the book cover showing the means for attaching the mechanism thereto;

Fig. 6 is a bottom view of a portion of one of the toggle plates, showing the paper holding prong in position thereon;

Fig. 7 is a section on line 7—7 of Fig. 6, with the prong in upright position, parts broken away;

Fig. 8 is a perspective view of the paper holding prong; and

Fig. 9 is a perspective view of the key.

In the assembling of paper holding mechanism on book covers it is desirable that the mechanism be constructed to form a self-contained unitary device and to provide simple means for attaching the same to a book cover whereby the user may readily disassemble the parts for replacement or repairs and the like, and for the purpose of changing the style or type of book covers when necessary or desirable. For these and other obvious reasons suitable means have been provided for accomplishing these results.

In the form of the device selected to illus-

trate one embodiment of the invention the paper holding unit or mechanism 9 comprises a spring plate or concave member 10 in which is mounted the toggle plates 11 and 12 which are held in position by means of inwardly extending flanges 13 and 14 on the spring member 10. The toggle plates are held in operative position within the concave spring member 10 by suitable means as the U-shaped clips or staples 15 which extend through cooperating slots 16 in the meeting edges of the toggle plates 11 and 12 and have their ends 17 bent over on said plates, as clearly shown in Figs. 1 and 3 of the drawing. The construction thus far described is well known in the art and it is not thought necessary to further describe the same.

The toggle plates 11 and 12 are provided with a plurality of sets of mating curved paper-holding prongs 24 which, in the position shown in Fig. 2, serve to hold the paper within the book, and in the position shown in Fig. 4, permit the paper to be removed or inserted.

An operating lever 18 is mounted at each end of the mechanism to facilitate the opening of the prongs. As best shown in Figs. 3 and 4 the body portion of each lever is in the form of an upright plate extending across the spring plate 10 in spaced relation to its intermediate portion and fulcrumed on its side portions adjacent to the flanges 13 and 14. A convex thumb piece 19 extends outwardly from the upper edge of the transverse plate and a finger 21 projects inwardly from the lower edge thereof and lies beneath the toggle plates 11 and 12.

When downward pressure is applied on the thumb piece 19, the lever 18 will rotate counterclockwise (Fig. 3) bringing the finger 21 against the underside of the toggle plates 11 and 12 adjacent to their articulated edges. The lever thus becoming of the first class, fulcrumed on the side portions of the spring plate 10 and prying upwardly on the toggle plates. The downward pressure of the fulcrum on the spring plate tends to flatten the concavity as it is seen in Fig. 4, moving the flanges 13 and 14 apart and thus relieving the pressure on the toggle plates and facilitating the rotation of the plates to the position shown in Fig. 4.

As best shown in that figure, the lower

edge 45 of the lever 18 is out of contact with the plate 10 between the points 46 and 47 on the side portions of the latter, insuring that the toggle bearings will be sufficiently near the edges of the plate to enable relatively small force to cause the yielding of the plate and with it the opening of the prongs.

The intermediate portion of the edge 45 and the finger 21 are spaced somewhat widely from the corresponding portion of the plate 10, as indicated at 20 in Figs. 4 and 5, to permit the insertion of a key for holding the mechanism to the book cover.

The operating lever 18 is held in position by inturned flanges 48 on the end of the spring member 10.

In forming attaching lugs on paper holding prongs of loose leaf binders, it has been proposed to provide tangential grooves in the prongs for engaging the toggle plates for holding the prongs in rigid relation to said plates. It is also common practice to strike up a portion of the outer periphery of the prongs to form the lugs so that they extend at right angles to the plane of the prongs. These ways of forming the attaching means for the prongs result in weakening the same at the attaching point, and not infrequently the prongs are broken off as a result of these constructions. In order to avoid weakening the prongs in forming the attaching lugs 25, these lugs are formed by pressing the material at right angles to the plane of the prongs. In other words, the lug 25 is formed in the plane of the prong by, what for convenience of description will be termed lateral pressure, on the outer portion of the material constituting the inner end of said prong. The pressing operation forms the shoulders 26 preferably at each side of the lug without removing any of the material of said prong.

The toggle plates are provided with rectangular slots 30 in which the lugs 25 of the prongs 24 are adapted to engage. The shoulders 26 engage the inner face of the toggle plates for positioning said prongs. The outer ends of the lugs 25 are spread or upset as shown at 27, see Figs. 6 and 7, for rigidly retaining said lugs in said slots. By forming and attaching the lugs in the manner described above the prong 24 at the attaching point is I-shape in cross section, and since none of the material has been removed it is materially strengthened at this point. This is considered an important feature of the invention since it provides a paper holding prong that, when in position, is as strong at its point of attachment as at any other point.

The prongs are arranged in pairs opposite each other to form a separable ring, as is usual in such constructions. The toggle plates will hold the prongs in either open or closed position, in the usual manner.

If desired, a finishing plate 28 may be secured over the toggle plates for concealing the same. The plate 28 is more or less resilient and is slightly convex, whereby the inwardly extending flanges 29 may be sprung outwardly to engage the edges of the spring plate or member 10, as shown in Fig. 4.

The operating levers 18 form end pieces to close the space between the plates 10 and 28 at the ends of the mechanism.

Suitable means are provided for securing the paper holding mechanism in position within a book cover 31. The cover may be of any suitable form and material, that shown comprising a back 32 and sides 33 and 34. Preferably cooperating loops and eyes or openings are provided on the back and paper holding mechanism for connecting the two together. As shown on the drawing a separate attaching plate 35 having loops 36 is employed. The attaching plate 35, which may be placed on the outer side of the back in the usual manner, or, if it is desired that the back have a finished appearance, the plate 35 may be and preferably is concealed between the laminations of the back as clearly shown in Figs. 2 and 3. The loops 36 at each end of the plate 35 extend through suitable openings 37 in the back 32, and corresponding aligned openings 38 in the plate 10. The parts are held in assembled relation by a key 39 at each end of the paper holding mechanism which is adapted to engage said loops. The inner walls of the loops are preferably inclined as at 41 to form guides or tapered openings for the keys 39 during their insertion. The keys may be tapered to guide them into the loops and are provided with bent ends 40 to facilitate their removal.

Any approved means may be employed for preventing the accidental removal of the keys 39. Preferably the keys are provided with depressions or lugs 43 which are adapted to engage one of the openings 38 in the plate 10. The resiliency of the parts will permit the withdrawal of the keys by pulling outwardly on the same.

In assembling the mechanism 9 on the book cover 31, the attaching plate 35, if it is not concealed within the back 32 is placed on said back with the attaching loops 36 extending inwardly through said back and through slots 38 in the plate 10. The keys 39 are inserted one at each end of said mechanism through the opening 20 and through the loops 36, the inclined faces of the loops guiding the keys and not only facilitating their insertion but serving to clamp the parts together. The engagement of the lugs 43 with the outer slots 38 of the plate 10 will hold the keys from accidental removal.

By means of this construction the loose leaf binder mechanism may be assembled as a unitary construction that may be readily

attached to or removed from a book cover without removing or disturbing any of the parts of the binder mechanism.

It is thought from the foregoing taken in connection with the accompanying drawings that the construction and operation of my device will be apparent to those skilled in the art, and that various changes in size, shape, proportion and details of construction 10 may be made without departing from the spirit and scope of the appended claims.

I claim as my invention:—

1. In combination, a book cover comprising a back, a plurality of loops having inclined inner walls extending inwardly from said back, a loose leaf binder mechanism having a curved resilient toggle operating plate provided with apertures for receiving said loops, and keys for engaging said loops for clamping said back and mechanism together.

2. In a device of the class described, the combination of a pair of toggle members articulated at their adjacent edges, the concave resilient plate having an opening in its intermediate portion, flanges on the resilient plate pivotally engaging the remote edges of the toggle members, a back having a loop projecting through the opening in the resilient plate, a key inserted through the loop above the resilient plate and a combined end piece and toggle operating lever extending transversely to the resilient plate above the key and fulcrumed at each side of the key, a thumb piece projecting outwardly from the lever and a finger projecting inwardly from the lever beneath the toggle members.

3. In a device of the class described, a pair of toggle members articulated at their adjacent edges, a concave spring plate having flanges yieldingly engaging the remote

edges of the toggle members, an end piece extending across the spring plate in spaced relation to its intermediate portion and fulcrumed on its side portions, a projection on the end piece beneath the toggle members and adapted to urge them upwardly when the end piece is rocked, a back beneath the spring plate having a loop extending above it, and a key between the spring plate and the end piece and extending through the loop.

4. In a device of the class described, the combination of a pair of toggle members articulated at their adjacent edges, a concave resilient plate having an opening in its intermediate portion, flanges on the resilient plate pivotally engaging the remote edges of the toggle members, a back having a loop projecting through the opening in the resilient plate, a key inserted through the loop above the resilient plate, an end piece extending transverse to the resilient plate above the key and fulcrumed at each side of the key, and means on the end piece to engage the toggle members.

5. In a device of the class described, a pair of toggle members articulated at their adjacent edges, a concave spring plate having flanges yieldingly engaging the remote edges of the toggle members, an end piece extending across the spring plate in spaced relation to its intermediate portions and fulcrumed on its side portions, a projection on the end piece beneath the toggle members and adapted to urge them upwardly when the end piece is rocked, a back beneath the spring plate and means for securing them together including a key extending between the spring plate and the end piece.

In testimony whereof I affix my signature.

JAMES C. DAWSON.
